Inventor
James Ostrander
By Frank H. Drury Atty.

UNITED STATES PATENT OFFICE.

JAMES OSTRANDER, OF INDIANAPOLIS, INDIANA, ASSIGNOR TO GRAPHO-METAL
PACKING COMPANY, OF INDIANAPOLIS, INDIANA, A CORPORATION.

PACKING.

Application filed November 8, 1919. Serial No. 336,682.

To all whom it may concern:

Be it known that I, JAMES OSTRANDER, a citizen of the United States, residing at Indianapolis, in the county of Marion and

5 State of Indiana, have invented new and useful Improvements in Packings, of which the following is a full, clear, concise, and exact description, reference being had to the accompanying drawing, forming a part 10 of this specification.

My invention relates to improvements in packing, and has for its object the production of a packing that will stand rough usage and wear better than ordinary packing 15 now on the market.

A further object is the production of a packing by the use of which a thin film of lubricant may be formed on the shaft.

20 A further object is the production of a packing in which the above features are combined with the advantage of cross expansion tending to keep the packing in place against the shaft and cause it to perform its function in the most efficient manner.

25 A further object is the production of a packing that can be cheaply manufactured, and one that will remain in operative position with little liability of displacement.

30 These and such other objects as may hereinafter appear are attained by my device, an embodiment of which is illustrated in the accompanying drawings, in which

35 Figure 1 represents a section view of my improved packing before compression;

Fig. 2 represents a top plan view of Fig. 1, with a portion of the upper layer broken away;

40 Fig. 3 represents a sectional view of my improved packing after compression.

Like numerals of reference indicate like parts, in the several figures of the drawings.

45 Referring now to the drawings,—my invention contemplates the use of a packing formed from strips of canvas, duck, or some fabric or fibre 4, having interposed between the layers a composition 5 of some rubber or rubberlike substance mixed with some 50 metallic, mineral, or mineral-like material.

The fabric is ordinarily supplied in wide strips and the composition 5 spread between to the desired degree of thickness, and the structure built up to the required thickness, as indicated in Fig. 1.

55 The material is then cut into strips of varying widths, depending upon the character of the packing required, and the strips so cut are placed in a press and compressed, causing the layers to assume a wrinkled or corrugated shape, as shown in Fig. 3 at 6. This construction brings in the principle of cross-expansion, as the packing being confined on the outside and inside is always tending to expand and hugs more closely 60 the shaft about which it is placed.

65 In practice with the ordinary rubber mixture, I use a grapho-metal composed in the main of soft metal in loculate condition with graphite embedded in its pores as described in United States Patent No. 926,676 issued to Septimus P. Morison. By the use of this composition I get excellent results; and the shaft, after a short use, is coated with a thin film of graphite, which acts as 70 a lubricant and eliminates skin friction.

75 A packing made in the above described manner wears much longer than other packing on the market, and the presence of the metal or mineral-like material greatly increases the efficiency of the product.

80 I can, if I desire, use lead without graphite, or graphite without lead, and I also find that the use of other comparatively soft metals, either alone or in combination with graphite, will also increase the value of the product, whether the layers are compressed or corrugated, or not.

85 The value of packing of this character depends greatly on its ability to maintain 90 its shape and serve in addition to the packing, as a lubricant, and this result is attained with a high degree of efficiency in my product.

95 I claim as new and desire to secure by Letters Patent of the United States—

1. A packing formed from a multiplicity of layers of fabric, with a layer composed of a mixture of rubber and metal interposed between said layers, said metal being in 100

loculate condition with graphite embedded in its pores.

2. A packing formed from alternate layers of fabric and a rubber-like composition including a lubricant, said fabric being wrinkled by the application of pressure.

3. A packing composed of alternate layers

of fabric and a rubber-like composition containing lead in loculate condition with graphite embedded in its pores.

10

In witness whereof, I have hereunto subscribed my name.

JAMES OSTRANDER.
